UNITED STATES PATENT OFFICE.

WILLIAM A. HANSEN, OF SAN FRANCISCO, CALIFORNIA.

GAS-ENGINE-STARTING DEVICE.

977,007.

Specification of Letters Patent. Patented Nov. 29, 1910.

Application filed July 3, 1909. Serial No. 505,906.

To all whom it may concern:

Be it known that I, WILLIAM A. HANSEN, citizen of the United States, residing in the city and county of San Francisco and State of California, have invented new and useful Improvements in Gas-Engine-Starting Devices, of which the following is a specification.

My invention relates to attachments for internal combustion engines.

It is designed especially to provide a means for scavenging the cylinder or cylinders of the burned gases which may remain therein when the engine stops, and to introduce into the cylinder a charge or charges of explosive mixture in readiness to be ignited when the switch is turned to complete an electrical circuit through the spark plugs or other igniting devices.

It consists in a combination of parts and details of construction which will be more fully explained by reference to the accompanying drawings, in which—

Figure 1 is an enlarged sectional view of the auxiliary carburetor or vaporizer. Fig. 2 is an enlarged sectional view of conducting passages and controlling cock. Fig. 3 is a similar view of the cocks and passages controlling the flow of the mixture to and from the cylinder. Fig. 4 is a modification of said device. Fig. 5 is a sectional view of one cylinder showing the connection of my device. Fig. 6 is a partial side elevation of four cylinders with the main and auxiliary carburetors and connecting pipes of my invention.

It is the object of my invention to provide a convenient means for scavenging or cleansing the cylinders of such burned gases and residue as may remain after the engine has stopped, and to introduce into the engine a charge of rich, combustible vapor which will readily ignite when the ignition devices are caused to operate, and thus start the engine without other labor.

As shown in the drawings, A represents the ordinary carburetor of any well-known or suitable description.

2 is the small auxiliary vaporizer or carburetor which may be conveniently attached to the carburetor A. The construction of this auxiliary vaporizer is well shown in Fig. 1. Gasoline or other hydrocarbon liquid enters the auxiliary vaporizer at 2, and may be supplied from the float chamber of the carburetor A through a pipe 3, Fig. 6.

The flow of the gasoline in this portion of the apparatus is controlled by a needle-valve 4.

Air under pressure is admitted through 5 into an interior chamber, through which chamber passes a short tube 6. This tube receives the gasoline which is admitted through the opening controlled by the needle-valve 4. Around the discharge end of this tube, and beyond the chamber which receives the air, is an annular passage 6a. The air rushing through this passage causes a suction or draft through the tube 6, in the manner of an injector, and this draws 70 the gasoline through the tube 6 and subdivides it into a fine spray, mixing it also with the air which is thus admitted.

Any suitable source of supply for air may be utilized. A convenient manner will be 75 to have a tank or receiver which is charged with air during the running of the engine, and always contains a sufficient supply. When the air is turned on it will, as before described, form a rich mixture with the 80 gasoline, and this passes upwardly through the pipe or passage 7 to the distributing chamber 8. This chamber has pipes or passages 9 leading to any number of cylinders which may compose the particular engine 85 to which the apparatus is applied. The application of four cylinders is shown in Fig. 6.

Each of the branch pipes is provided with a double cock, as at 10, Fig. 3. 11 is an 90 inlet passage, and 12 is an outlet passage. A small pipe 13 connects this passage with an intake opening 14 on one side of the cylinder, as shown in Fig. 5. The explosive mixture is admitted into a pocket or chamber 95 between the spark plug and the main inlet valve, thus insuring a rich mixture around the spark plug. The gas then flows into the cylinder, and filling this, it then discharges through the passage 15. These passages are closed in unison by cock 16, Fig. 3. This cock has an arm 17 and a connecting rod 18 leading to any desired convenient point for operation. The passages are thus all opened and closed in unison. One of 105 the cocks, as at 19, Fig. 2, may have, in addition to the passages 11 and 15, an extra passage 20 to control the air supply to the auxiliary vaporizer. The air, as previously stated, may be taken from any suitable supply under pressure, and enters at 21, passing through the passage 20, thence through the

pipe 22 and into the supplemental vaporizer at 5, as before described. It will thus be seen that when, by means of the rod or connection 18, the arm 17 is moved to open the 5 cock, the air passage in cock 19 is opened simultaneously with the other passages. The air will then rush into the auxiliary vaporizer, drawing in gasoline, as before described, passing thence into the distributor 10 8, and from thence into the branch pipes 9 to the different cylinders, which are thus charged.

In Fig. 4, I have shown a modified form of double cock. In this case the gas enters 15 at 11', passes down through the passage 12', and discharges into the cylinder through the passage 13' at right angles, as indicated by the arrow. The gas being thus forced under pressure fills the cylinder and commences to discharge through the passage 15' 20 as soon as the cylinders are filled, after which the cocks may be closed, and upon proper ignition through the spark plugs, or equivalent devices, the engine will be 25 started, after which it will draw its regular supply from the main carburetor in the usual manner.

Having thus described my invention, what I claim and desire to secure by Letters Patent is—

1. The combination with an internal combustion engine, and a main carburetor, of a supplemental vaporizer, a hydrocarbon supply device between the main carburetor and 35 said vaporizer, and a controlling needle-valve, a chamber, means for admitting air under pressure into said chamber, a pipe conducting gasoline through said chamber, said chamber having an annular exterior 40 passage for the air, and a distributing chamber into which the mixture is admitted and from which it is delivered to the cylinders.

2. The combination with an internal combustion engine, and the main carburetor, of 45 a supplemental carburetor, means for admitting and controlling a supply of hydrocarbon thereto from the main carburetor, a mixing and distributing chamber, pipes leading therefrom, a cock located at one 50 side of the cylinder having a plurality of passages therethrough, means for opening and closing it, and a pipe leading from one passage of said cock and discharging into a chamber contiguous to the igniting device 55 of the engine, from which the charge acts to scavenge the cylinder and discharge through the first-mentioned cock.

3. The combination with an internal combustion engine, and a supplemental carburetor, of means to control the flow of gas 60 from the carburetor, said means including

cocks having a plurality of passages, one of which communicates with the intake opening of the cylinder, and the other with the exhaust.

65

4. The combination with an internal combustion engine, of a means to supply an explosive starting mixture thereto, said means including cocks having a plurality of passages, one of which communicates with the cylinder intake opening, and the other with the exhaust, and mechanism by which said passages are opened and closed in unison.

70

5. The combination with an internal combustion engine, and a supplemental carburetor, of cocks having a plurality of passages, certain of which communicate respectively with the intake and the exhaust, and certain with the supplemental carburetor and a source of air supply.

75

6. The combination with an internal combustion engine, and a supplemental carburetor, of cocks having a plurality of passages, one of which connects the carburetor with the intake of the cylinder, certain others connect the carburetor with a source of air supply, and connect the cylinder combustion chamber with the exhaust.

80

7. The combination with an internal combustion engine, and a supplemental carburetor, of cocks having a plurality of passages, one of which connects the carburetor with the intake of the cylinder, certain others connect the carburetor with a source of air supply, and connect the cylinder combustion chamber with the exhaust, and manually controlled mechanism to rotate the plug of the cock and open and close all the 90 passages substantially in unison.

100

8. The combination with an internal combustion engine and a main carburetor, of a supplemental vaporizer, means for regulating the supply of hydrocarbon thereto from the main carburetor, means for admitting 105 and mixing air under pressure with the hydrocarbon in said supplemental vaporizer, a distributing chamber connected to said supplemental vaporizer, pipes leading therefrom to the engine cylinders, manually controlled cocks in said cylinders to which the 110 said pipes are connected, each having a scavenging passage, and passages discharging at right angles to said scavenging passages.

115

In testimony whereof I have hereunto set my hand in the presence of two subscribing witnesses.

WILLIAM A. HANSEN.
